(57) **CLAIM**

The ornamental design for a soft pocket package for absorbent tissue sheets having a sail shaped opening, as shown and described.

DESCRIPTION

FIG. 1 is a perspective view from front, above and left end; FIG. 2 is a front view;

FIG. 3 is a back view;

FIG. 4 is an end view;

FIG. 5 is an end view;

FIG. 6 is a top view;

FIG. 7 is a bottom view;

FIG. 8 is a perspective view of alternative embodiment; and, FIG. 9 is a perspective view of said alternative embodiment in a position of use.

The broken lines showing of tissue papers in FIG. 9 are for illustrative purpose only and forms no part of the claimed design.
